ASPHALT SURFACER

James H. Woods, San Fernando, Calif.

Application November 20, 1950, Serial No. 196,577

6 Claims. (Cl. 158—13.6)

1

This invention relates to an asphalt surfacer and is exemplified by such a portable surfacer which may be manually pushed back and forth by a single workman along cracks or patches in an asphalt roadbed or the like, so as to smooth the same under the influence of heat and pressure supplied by the moving member.

Previously there have been handable surfacers consisting essentially of a metal contact shoe secured to an elongated rod or operating handle. The surfacers were heated by laying the shoe end in a fire for a while. After a short period of use, the shoe had cooled off to such an extent that it had to be returned to the fire for reheat-ing. This not only restricted the weight of such a unit to that which a workman could repeatedly lift into and out of the fire. It also exposed the shoe to the aging influence of the fire for consider-able periods of time when the shoe was not actually being used. The period of effective operation after removal from the fire was com-paratively brief so that several surfacers might be required to work a comparatively small area of asphalt. Moreover the time and fuel con-sumed in setting up and heating was out of all proportion to that during which the iron was in actual use. Sometimes the use is sporadic and over some distance. The disadvantages of cus-tomary methods under such circumstances render them antediluvian.

Accordingly it is an object of the invention to provide a portable surfacer having a self-con-tained heating source or fire box. Such a unit conveniently operates by providing a flame spread over the upper face of the contact shoe so that the heat from the same is conveyed thru the metal shoe to the bottom contact blade or surface. A further advantage of such construction is that worn shoes may be replaced on the unit from time to time by bolting or otherwise attaching the same to the remainder of the upper part.

Yet another object of the invention is to pro-
vide such a handable surfacer having a self-con-tained fuel supply. Such fuel is conveniently a liquid such as petroleum derived material and by the present construction, the fuel tank is lo-cated in such manner as to produce a low center of gravity of the unit and to add its weight to that of the shoe itself so as to transmit the same to the pavement being worked.

In this connection, there is further provided means for increasing the effective weight of the surfacer by accumulating compressed air therein. Desirably this pressure may be built up, by a manu-
55
ually operable, self-contained pump, and ap-

2

plied to the upper surface of the fuel supply thus aiding its out flow.

Still another purpose is to provide such a unit having a flame nozzle exposed to external cooling air but at the same time adequately encased so as to guard the same against possible injury upon the unit being roughly handled as when it may be thrown into or out of a supply truck.

Yet another object resides in the provision of such a unit embracing a tubular handle which carries the fuel tank and fire box in a continually descending line toward the shoe, with the interi-ors of the handle, and fuel tank disposed in open communication so that the handle may 15 serve simultaneously as a feed line for the fuel and as a housing for an air compression pump.

In the drawings:

Figure 1 is a perspective view of a preferred form of my asphalt surfacer in position for use.

20 Figure 2 is a longitudinal sectional view taken thru the upper or handle end of the device and particularly showing the construction of the air pump mounted therein, with portions shown in elevation.

25 Figure 3 is a longitudinal sectional view taken thru the lower portion of the surfacer, with parts in side elevation, and particularly showing the relation of the flame nozzle to the interior of the surfacing shoe.

30 Figure 4 is a transverse sectional view taken thru the contact end of the surfacer as seen along the line 4—4 of Figure 3 and showing the guide fins for spreading the flame within the heat chamber.

35 Figure 5 is a vertical sectional view taken thru the shoe and cover member as seen along line 5—5 of Figure 3 and particularly showing the forward ventilating apertures at the front end of the device.

40 Having particular reference to the embodiment of the invention illustrated in Figure 1, there is provided a portable or hand operated asphalt surfacing device embodying a lower terminal contact head A, a combustion unit B immediate posterior thereto, a fuel container C, and an elongated handle or operating portion D.

The device is of such relatively limited weight so as to enable it to be readily lifted in and out of a truck by one or two workmen and in use 45 to permit it to be pushed slowly back and forth over the asphalt service by a single operator. At the same time it should be noted that the unit may optionally be so balanced as to be able to stand by itself unsupported, and has the bulk of its weight concentrated at the lower end so as to

apply the same most effectively to a work area on pavement. This likewise facilitates the ready turning or lateral movement of the device about a given spot by the operator.

The contact head A is formed by a basal shoe 10 constructed of heavy metal or the like and characterized by a lower blade surface 12 which is generally flat over most of its area but curved upward at the front 14 and rear 16 edges in a generally arcuate pattern so as to permit the same to ride easily over temporary elevations on the surface being treated. The upper face 18 of the shoe is provided with a shallow, generally dish-shaped depression 20, set back a short distance from each edge and generally otherwise coextensive with the horizontal area of the shoe. The surrounding periphery or ledge 22 of the shoe is adapted to support an overlying hood or closure member 24 which, in conjunction with the bottom of the depression 20, forms an inner, generally rectangular heat or combustion chamber 26.

The hood is constructed with a flat top 28 and downwardly diverging side walls 32 the lower edges of which abut upon the respective sides of the ledge 22, being secured thereto by welding or are generally vertical or parallel to each other, the former being provided with vertically directed slits or apertures 38 which jointly form a grill in the forward end so as to provide an outlet for a longitudinal air passage thru the combustion chamber 26.

To the rear of the combustion chamber there is located a generally cylindrical housing 40 secured at an upright angle to the contact head A with its edges abutting and bolted (as by vertical studs not shown) or welded to the rear edge 42 of the shoe and the rear wall 36 of the hood. The hollow interior of the housing 40 accordingly is in open communication with the combustion chamber 26 thru the aperture 41 of the rear hood wall 36 (Figure 4). The housing 42 is constructed of a lower peripherally enclosed section 44 and an upwardly continuing portion 46 of substantially semi-circular or trough-like shape. Thus, the upper half of the latter section being cut away, it serves both as an entry for air to the lower section and as a semi-housing frame for combustion unit B.

The combustion unit or mixing tube which is mounted in the supporting channel 40 provides a jet or nozzle member 48 the forward, lower, somewhat constricted, end 50 of which is disposed to emit a downwardly directed flame which is initially ignited in the upper section thereof. The mixing tube is supplied with fuel thru a line 52 and a primary supply of air is drawn in thru the opening 54. The capacity of the air inlet 54 is in turn regulated by a longitudinally displaceable valve 56 which can be manually adjusted by means of the hand wheel 58.

Additional or secondary air ducts are provided in the lower portion of the nozzle at 60. In this connection, it is important to observe that the outlet or lower end of the jet 48 is overlaid by the tubular housing 44 spaced apart therefrom so as to prevent the former from becoming deformed upon the unit being roughly handled as when it is being thrown in or out of a truck. At the same time air is permitted to pass downward between the housing wall 44 and the outside of the nozzle and thru the aperture 41 so as to support further combustion in the chamber 26. As the flame or combustion products enter the chamber 26 they contact an upstanding baffle 61 formed of a pair of diverging fins which serve to spread

the burning or heated gases over the area of the chamber.

A fuel container C is provided with the unit, being formed integral therewith and located comparatively close to the contact head A so as to contribute to the low center of gravity of the composite device. The fuel employed, for example, may be gasoline and as here illustrated my fuel tank 62 is a generally cylindrical container the lower end 64 of which is rigidly secured to the edge of the channel member 46 as by welding and is apertured at 66 for threaded connection to the delivery line 52.

The opposite end 68 of the tank supports the outwardly extending handle unit D by means of an L-shaped or flanged mounting collar 70 which is fastened axially to the end wall 68 with its central opening 72 in alignment with a similar opening 74 of the end wall so as to receive jointly therethru, the mouth of a tubular member 76, the interior of which is in open communication with the inside of the gasoline tank for a purpose which will be shortly explained.

The tubular member 76 extends axially upward from the fuel tank 62 to a point of bending 78 where it is curved rearward at a greater angle so as to form a more convenient hand hold portion 80 for the operator. Within this terminal section 80 (Figure 2) there is provided a manually operable air pump 82 by means of which a positive pressure of air can be built up upon the upper surface of the gasoline in the tank 62 (or in the tubular portion 76 if the gasoline extends up this far).

The air pump is carried in a central aperture 84 of an annular cap member 86 which latter serves as well as a closure for the upper end of the tube 76. The cap is provided with a radially enlarged lip 88 bearing internal screw threads 90 which register with corresponding external threads 92 about the mouth of the tube. The elongated cylindrical pump unit 82 is permanently mounted within the cap 86 as by soldering and projects outward beyond either end therefrom so that upon mounting the cap 86 upon the handle 80, the lower portion of the pump is inserted in the tube and at the same time the tube is closed to the exterior. Upon the cap and pump being taken off, the fuel tank 62 can be filled by pouring gasoline down the handle 80.

The air pump 82 consists of a tubular member 92 opened at both ends and having a one-way valve 94 located at the lower end thereof, the valve being normally held closed by a spring 96 disposed about the valve stem 98. A closure cap 100 substantially U-shaped in axial section, is threadedly mounted upon the opposite end of the tube 92 and journals in a central aperture thereto, a piston rod 102 which is thus disposed for reciprocating movement within the tube 92. The inner or lower end of the piston rod 102 carries the plunger or piston proper 104 which is moveable lengthwise in the tube to force air thru the valve member 94. The outer end of the piston rod 102 is in turn attached to a U-shaped cap 108 which is of generally corresponding diameter to the handle 80 and consequently overlies the inner cap 100 and most of the outwardly projecting portion of the pump housing 92.

Upon outward movement of the cap 108, the plunger rod of course moves out simultaneously, the two being withdrawn until the piston head is behind an air inlet 110. Inward movement of the cap and piston rod forces the newly entered air from the piston chamber past the valve 94

and compresses it into the handle 16. A helical spring 112 disposed about the piston rod and attached to the inner face of the end of the cap 108 provides both a shock absorber and a limit means for inward movement of the piston and attached cap, the free end of the spring 102 thus abutting against the outer face of the closure member 100 as seen in Figure 2.

Another feature of this invention is the provision of a baffle 114 within the bottom of the cylinder barrel or channel 40. By this construction an open pan is effectively provided beneath the burner B so that upon initial stoking of the latter liquid fuel can drip down into the area beneath the burner to heat the same as required to "fire up." When so used the apparatus is preferably inclined so that the liquid fluid level, as shown at 116 in phantom, is horizontal. Any excess easily burns away or when the apparatus is righted for use runs down into the fire chamber 26 where it is consumed with the main firing flame.

Accordingly, it will be seen that I have provided an asphalt surfacer which is both compact and efficient in construction as well as simple and economical in operation. As earlier noted, the shoe proper may be disconnected from the rest of the unit after use, along the time of attachment and a new shoe connected. Thus the unit as a whole has a greatly extended period of usefulness.

While I have herein shown and described my invention in what I have conceived to be the most practical and preferred embodiments, it is recognized that departures may be made therefrom within the scope of my invention, which is not to be limited to the details disclosed herein, but is to be accorded the full scope of the claims so as to embrace any and all equivalent devices.

The invention having been herein described, what I claim as new and desire to secure by Letters Patent is:

1. A portable asphalt surfacer comprising a smooth-bottomed surface contacting metal shoe including a hood forming a combustion chamber over the area of the shoe, said chamber having an intake at one end, a baffle across the intake, an integral tubular extension on the shoe angularly disposed thereto adjacent the baffle and a burner projecting into the tubular extension, said extension being notched on an upper side thereof above the tubular extension and adapted to accommodate the burner in nested relation therein accessible through said notch, a fuel tank supported on the upper end of the tubular extension integral with and forming an intermediate portion of a handle, a tubular member openly communicating with the upper end of the fuel tank extending upwardly out of the tank forming a hand-hold and a hand pump mounted in the upper end of the handle, said handle providing an outer casing and an air conduit for said pump.

2. A portable asphalt surfacer comprising a smooth-bottomed surface contacting metal shoe including a hood forming a combustion chamber over the area of the shoe, said chamber having an intake at one end, a baffle integral with the shoe and across the intake, a tubular extension on the shoe angularly disposed thereto adjacent the baffle and a burner projecting into the tubular extension spaced from the baffle, said extension forming a part of a handle and being open on the upper side thereof above the firebox and adapted to partially encircle and guard the

burner, a low transverse wall across a portion of the extension which is open forming fire-up reservoir for fuel, a fuel tank on the extension above the firebox and a hand-hold on the handle above the reservoir.

3. A portable asphalt surfacer comprising a smooth-bottomed surface contacting metal shoe including a hood forming a combustion chamber over the area of the shoe, said chamber having an intake at one end, a baffle across the intake of the chamber, an integral tubular extension on the shoe angularly disposed thereto adjacent the baffle and a burner projecting into the extension, said extension being open on an uppermost side thereof and adapted to accommodate the burner, a low transverse wall across the extension forming a fire-up reservoir for fuel, a fuel tank integral with and forming a mid-portion of a handle, a tubular hand-hold at the uppermost end of the handle openly communicating with the fuel tank, and a hand pump in the upper end of the handle for pumping air through said handhold and into said reservoir, and a gas supply tube from the tank to the reservoir wholly nested in the tubular extension.

4. A portable asphalt surfacer comprising a smooth-bottomed surface contacting metal shoe including a hood forming a combustion chamber over the area of the shoe but inset from the front end of the shoe, said chamber having an intake at a rear end, an outlet at a front end behind and above the front end of the shoe and a baffle across the intake, an integral tubular extension on the shoe angularly disposed thereto adjacent the baffle and a burner projecting into the extension, said extension forming part of a handle and having a cut-away portion on the upper side thereof above the burner adapted to accommodate the burner, a low transverse wall across the extension adjacent the burner forming an open fire-up reservoir for fuel, a substantially cylindrical fuel tank integral with and forming an intermediate portion of the handle, a tubular member extending upwardly out of the tank forming a hand-hold and a pump casing and air pressure pump therein in axial alignment with and forming the upper end of the hand-hold.

5. In a portable asphalt surfacer, in combination, a substantially flat shoe of rectangular configuration in plan view, having rounded edges at the bottom thereof, a flat upper surface portion, and having a central dished-out surface, including an upstanding, integral, substantially L-shaped baffle extending upwardly beyond the upper dished surface beyond the plane of the flat upper surface portion of the shoe and having its apex directed rearwardly, a hood having a top and sides, said sides being secured to said flat surface portion at the sides of the shoe, said hood being open at the rear end disposed above said dished portion of the shoe behind said L-shaped baffle, and a front end having openings defined therein, a cylindrical housing extending upwardly and rearwardly of said hood and shoe and being secured thereto in communication with the rear opening of the hood and said dished surface of said shoe, an upper side portion of said housing being notched, a burner nested within the notched housing portion and having a flame tip projecting downwardly and forwardly within the unnotched lower portion of the cylindrical housing, a transverse partition in the cylindrical housing opposite from said notch and adjacent said burner, a cylindrical reservoir having a threaded lower wall integral with an uppermost end of said

cylindrical housing, said lower wall extending radially beyond said housing and said burner, a fuel line communicating between said reservoir and through said wall thereof and said burner and nested well within said notched cylindrical housing, a tubular handle extending upwardly and rearwardly, coaxial with said housing and said reservoir and communicating with the latter, an upper end of said handle being screw-threaded, a cap threadably secured thereto and having a central opening, an air pump extending into said handle through said cap by means of said opening for pumping air under pressure into said handle and said reservoir, said cap being threadably removable from said handle together with said pump for filling said reservoir and said handle through said handle.

6. An asphalt surfacer as defined in claim 5,

said shoe extending forwardly substantially beyond said hood, said hood front openings being forward and adjacent said dished portion of said shoe.
